DEISTER MACHINE COMPANY, OF FORT WAYNE, INDIANA, A CORPORATION OF
INDIANA.

CONCENTRATING TABLE.

Application filed September 22, 1924. Serial No. 738,966.

The invention relates to concentrating tables of the transversely inclined, differentially reciprocated type.

In the concentration of various ores on concentrating tables the practice formerly was to size or classify the materials into roughing feeds, sand table feeds and slimes and then treat the classified feeds separately on tables designed therefor. Later, instead of classifying the materials, the entire mixture of table feeds was first treated on a roughing table, and then the roughed concentrates were cleaned on a finishing or cleaning table. The tailings were then reground and treated on sand tables or in flotation devices or treated on a combination of such tables and devices. This later practice has continued generally up to the present time. In carrying on the foregoing operations not only are numerous tables required to do the work but a large amount of floor space is thereby taken up or occupied by the machines, and the cost of operation is relatively high.

The object of our present invention is to provide a table upon which the roughing process and the concentration of mixed materials are carried on simultaneously and thereby accomplish a great saving in the number of machines, in the necessary floor space and cost of operation. Other objects and advantages of the invention will be set forth hereinafter.

The invention consists in a table having upon its concentrating surface a main stratifying or roughing section, a secondary concentrating section and a final cleaning section, the secondary and final cleaning sections being progressively higher than the main section, and a resistance plane being disposed along the rear edge of each section.

An embodiment of the invention is illustrated in the accompanying drawings, in which

Figure 1 is a plan view of the deck of a table embodying the invention; Fig. 2 a cross-sectional view on line 2-2 of Fig. 1; Fig. 3 a cross-sectional view on line 3-3 of Fig. 1; Fig. 4 a cross-sectional view on line 4-4 of Fig. 1; Fig. 5 a cross-sectional view on line 5-5 of Fig. 1; Fig. 6 a cross-sectional view on line 6-6 of Fig. 1; Fig. 7 a plan view of the deck with the riffles, the covering, the feed box and the dressing water

launder removed to illustrate the relative positions of the several sections of the surface of said deck; Fig. 8 an enlarged cross-sectional view on line 8-8 of Fig. 1; Fig. 9 an enlarged cross-sectional view on line 9-9 of Fig. 1 and Fig. 10 an enlarged cross-sectional view on line 10-10 of Fig. 1.

The deck 1 of the table is suitably supported for differential reciprocation longitudinally by suitable mechanism, the motion mechanism being connected to the deck at its head end 2 and the direction of reciprocation being indicated by the arrow at said end of the deck. A high board 3 extends along the head end of the deck and a high board 4 extends along the feed and dressing water side 5 of the deck. A feed box 6 is suitably supported above the deck at the side 5 adjacent the head end of the table and a dressing water launder 7 is also supported above the deck and extending from the feed box toward the concentrates discharge end of the deck. The materials mixed with water are fed into the feed box 6 from which they descend onto the deck.

The deck in operating position slopes transversely downwardly from the feed and dressing water side 5 toward the tailings discharge side 8, and in a longitudinal direction the deck is preferably level, its concentrating surface being composed of a series of sections which differ in their height as about to be described.

A main stratifying plane or section 9 is formed at the head end of the deck and extends along the tailings discharge side 8 from the head end toward the concentrates discharge end 10 of the deck and also for a much lesser distance along the feed side 5, so that its forward edge, indicated by the line *a-a*, is oblique to the line of reciprocation of the deck. Co-terminating with the section 9 on the line *a-a* is a resistance plane 11 which slopes upwardly toward the concentrates discharge end 10 of the deck and co-terminates at its forward or upper edge with a plateau 12 that is substantially parallel with the main plane 9. The co-terminal line *b-b* between the resistance plane and the plateau 12 is substantially parallel to the coterminal line *a-a*. Forwardly of the plateau 12 and co-terminating with it on the line *c-c* that is substantially parallel to the

line $b-b$ is a second resistance plane 13 which also slopes upwardly toward the concentrates discharge end 10.

The upper edge $d-d$ of the second resistance plane 13 is substantially parallel to the coterminous line $c-c$, and said edge is coterminous with a second plateau 14. The forward edge, $e-e$ of the plateau 14 is less oblique to the line of reciprocation than the rear edge thereof at $d-d$. Hence the top surface of the plateau is substantially triangular in shape and has a much greater area than the plateau 12. Forwardly of the plateau 14 and coterminating with it on the line $e-e$ is a third resistance plane 15 which slopes upwardly toward a third plateau 16 that extends along the concentrates discharge end 10. The plateau 16, in the present illustrative embodiment of the invention is also triangular in shape and is much larger than the plateau 14.

From the foregoing description it is apparent that from the head end of the deck toward the concentrates discharge end 10 the surface of the deck is formed with a main stratifying plane 9 and three plateaus with resistance planes connecting them so that the plateaus progressively increase in height toward the concentrates discharge end 10 of the deck.

The surface of the deck, as above described, is covered with linoleum 17 or other suitable covering and secured to the deck over the covering is a series of riffles extending from the head end toward the concentrates discharge end 10 of the deck. The form of the riffles is peculiar in the present embodiment of the invention. On the main stratifying plane 9 the riffles 18 are substantially parallel to the line of reciprocation of the table. They are relatively high at their upper sides and reduce in height transversely as shown in Fig. 8, the reduction in height being toward the tailings discharge side of the table. These riffles 18 are extended onto and across the resistance plane 11, the lower plateau 12 and the resistance plane 13 and their forward portions for a selected distance rearwardly of their extremities are also tapered longitudinally toward said extremities.

Cap riffles 19 are secured to the tops of the main riffles 18, their forward ends terminating at the crest of the first resistance plane 11, the forward ends of the cap riffles being also tapered longitudinally for a selected distance rearwardly of their tips. The cap riffles are valuable when mixed feeds are treated on the table and they may be omitted if a classified feed is treated on the table. On some ores it is efficacious to so secure the cap riffles to the main riffles that they overhang the upper sides of those riffles, as shown in Fig. 8. The overhanging cap riffles tend to hold the minerals in the

riffle troughs and prevent their escape over the tops of the riffles, and they are especially valuable when the materials to be treated are fed to the table in large quantities.

On the intermediate plateau 14 and the adjacent resistance plane 15, the riffles 20 are of cleat form and relatively narrow and shallow (Fig. 10) and also taper longitudinally at their forward ends. There are substantially twice as many of the riffles 20 as there are main riffles 18.

The extension riffles 21 on the uppermost plateau 16 are the lowest riffles on the deck. They extend toward the concentrates discharge end 10 of the deck at any selected angle with respect to the line of reciprocation of the table. In the present adaptation of the invention the extension riffles 21 extend upwardly on the transversely inclined plateau 16. Where very lean ores are treated on the table the extension riffles may be omitted.

When the table is properly adjusted as to inclination and it is in operation, the materials with water descend on to the deck at its upper side and underneath the feed box and tend to flow down the transverse slope of the main section 9. The riffles retard the flow of the materials on said slope, which together with the reciprocating movement of the table, cause the materials to stratify on the surface 9 in accordance with their specific gravities. The light gangue flows over the tops of the riffles to the tailings discharge side and the reciprocating movement of the deck advances the caught materials toward the concentrates discharge end 10 of the deck. When the caught materials reach the first or lower resistance plane the coarse light gangue, being in the upper stratum, is held back and some of it passes over the riffles on said plane toward the tailings discharge side since the riffles thereon taper longitudinally. The minerals and gangue remaining with them pass onto the lower plateau where further elimination of light gangue takes place.

The feed then passes up the intermediate resistance plane where the gangue in the upper stratum is held back and washed over the longitudinally tapered riffles thereon to the tailings discharge side. The materials retained by the riffles on the intermediate resistance plane pass onto the intermediate plateau. The coarse light gangue is practically removed by the time the materials reach the intermediate plateau. Such gangue as is with the minerals is relatively fine. This plateau, being substantially triangular in shape, has substantially a shearing action on the fine gangue and since the riffles are more numerous and lower than the main riffles and also taper longitudinally the values are held on the plateau while the

lighter gangue is sheered off by the wash water, the final resistance plane holding back the gangue similarly to the preceding resistance planes. Hence a secondary concentration of the feed is effected on the intermediate plateau. Such fine gangue as reaches the final plateau is largely washed out by the wash water and the concentrates, passing off the plateau at the concentrates discharge end, are very largely free from gangue.

It is thus seen that the feed is stratified on the main stratifying section 9, the coarser gangue being removed on the lower resistance plane, the lower plateau and the intermediate resistance plane. Hence the roughing process is carried on up to the intermediate plateau. Since the area of the intermediate plateau is relatively large and gangue that reaches it is relatively fine a secondary stratification of the materials that reach this plateau takes place, the values being finally cleaned on the third plateau. Hence the table is in effect both a roughing and a finishing table.

When the table is properly adjusted as to inclination and flow of dressing water, it will operate efficiently without further adjustment irrespective of the feed—whether the feed varies in quantity or quality, and the line of separation between the gangue and the mineral remains constantly at its proper place on the deck. Hence the table, after it has been properly adjusted, automatically controls the line of separation between the gangue and the values through all variations in the feed.

Since the table of our invention is both a roughing and a finishing device it eliminates roughing tables and sand or finishing tables and hence effects a large saving in labor, time, money and floor space.

What we claim is:

1. In a concentrating table, a deck having upon its concentrating surface a roughing section and a finishing section, transversely tapered riffles on the roughing section and tapering longitudinally in their forward portions, cap riffles secured to the tops of the transversely tapered riffles adjacent the high sides thereof, shallow riffles on the finishing section adjacent the concentrates discharge end of the deck and shallow riffles on the latter section between the forward ends of the transversely tapered riffles and the rear ends of the first named shallow riffles and being greater in number than the said transversely tapered riffles.

2. In a concentrating table, a deck having upon its concentrating surface a roughing section and a finishing section, relatively high transversely tapered riffles on the roughing section, cap riffles secured to the said high riffles and overhanging the high sides thereof, relatively shallow and narrow

riffles on the finishing section and being greater in number than the high riffles and shallow riffles on the finishing section forwardly of the forward ends of the relatively shallow and narrow riffles and disposed at an angle to the latter riffles.

3. In a concentrating table, a transversely inclined and differentially reciprocating deck having upon its concentrating surface a roughing section and a two portion finishing section between the roughing section and the concentrates discharge end of the deck, one of said portions being adjacent the said concentrates discharge end of the deck, relatively high transversely tapered riffles on the roughing section having their forward ends longitudinally tapered, cap riffles secured to the tops of the said high riffles adjacent the high sides thereof respectively, riffles on the adjacent portion of the finishing section that are parallel to the relatively high riffles and being lower in height and narrower and greater in number than said high riffles and riffles on the second portion of the finishing section that are lower than those on the other portion of said section and extend upwardly on the transverse slope of said second portion of said section.

4. In a differentially reciprocating, transversely inclined concentrating table, a deck having upon its concentrating surface a roughing portion consisting of a main stratifying section, a diagonally disposed plateau forwardly of the main section, a resistance plane between the main section and said plateau, an upwardly inclined resistance plane at the forward side of the plateau, the said concentrating surface also having thereon a finishing portion consisting of a secondary concentrating plateau, an upwardly inclined resistance plane adjoining the forward side of the secondary plateau and a final cleaning plateau between the latter resistance plane and the concentrates discharge end of the deck.

5. In a differentially reciprocating, transversely inclined concentrating table, a deck having upon its concentrating surface a roughing portion consisting of a main stratifying section, a diagonally disposed plateau forwardly of the main section, a resistance plane between the main section and said plateau and an upwardly inclined resistance plane adjoining the forward side of the said plateau, the said concentrating surface also having thereon a finishing portion consisting of a secondary concentrating plateau and a final cleaning plateau, a resistance plane between the two latter plateaus, main riffles on the roughing portion extending in a direction substantially parallel to the line of reciprocation of the table, said riffles being tapered transversely and their forward ends being tapered longitudinally and relatively shallow riffles on the secondary con-

centrating plateau that are greater in number than the main riffles.

6. In a differentially reciprocating, transversely inclined concentrating table, a deck having upon its concentrating surface a main stratifying section, an intermediate secondary concentrating section and a final cleaning section, the intermediate section being higher in elevation than the main stratifying section and the final cleaning section being higher in elevation than the secondary concentrating section and disposed along the concentrates discharge end of the deck, resistance planes between the sections, and riffles on the sections and resistance planes, the riffles on the intermediate section being lower and greater in number than those on the main section.

7. In a differentially reciprocating, transversely inclined concentrating table, a deck having upon its concentrating surface a main stratifying section, an intermediate secondary concentrating section and a final cleaning section, the intermediate section being higher than the main section and the final cleaning section being higher than the intermediate section, an inclined resistance plane along the rear side of each of the elevated sections, and riffles on the said sections and said resistance planes, the tops of the riffles on the main section being transversely inclined downwardly toward the tailings discharge side of the deck and the riffles on the intermediate section being greater in number and less in height than the riffles on the main section.

8. In a differentially reciprocating, trans-

versely inclined concentrating table, a deck having upon its concentrating surface a main stratifying section extending from the head end of the deck toward the concentrates discharge end thereof, a series of three plateaus on said surface between the forward side of the main section and the concentrates discharge end of the deck, each plateau being higher than the main section and higher than the plateau rearwardly of it, a resistance plane between the main section and the first or lowest plateau and disposed at an oblique angle to the direction of reciprocation of the deck, a second resistance plane between the first and intermediate plateaus and disposed similarly to the first named resistance plane, a third resistance plane between the intermediate and third plateaus and disposed at an oblique angle to the direction of reciprocation but less oblique than the preceding resistance planes whereby to form the intermediate plateau with a larger area than the first plateau, main riffles substantially parallel to the line of reciprocation of the table and extending on the main stratifying section and across the first plateau and adjoining resistance planes to the rear side of the intermediate plateau, riffles on the intermediate plateau that are lower and narrower and greater in number than the main riffles.

In witness whereof we have hereunto subscribed our names this 13th day of September, 1924.
